H. M. Plaisted,
ATTORNEY,

UNITED STATES PATENT OFFICE.

LEONARD WOODS, OF ST. LOUIS, MISSOURI.

REVOLVER.

1,150,566.

Specification of Letters Patent. Patented Aug. 17, 1915.

Application filed January 19, 1914. Serial No. 812,991.

To all whom it may concern:

Be it known that I, LEONARD Woods, citizen of the United States, residing at 3644 Botanical avenue, in the city of St. Louis 5 and State of Missouri, have invented certain new and useful Improvements in Revolvers, of which the following is a specification.

This invention relates to certain new and useful improvements in revolvers.

10 The object of my invention is to provide a revolver or multi-shot pistol of effective construction and operation as an improvement on the single-shot pistol shown in my Patent 1,073,312 dated September 16th, 1913. To this end my improvements have 15 reference to a revoluble cylinder chambered for cartridges; have reference to a trigger and hammer mechanism coöperating with said cylinder; and have reference to other 20 features hereinafter described and claimed.

In the accompanying drawing in which like reference letters indicate corresponding parts, Figure 1, represents a top view of a pistol exemplifying my invention; Fig. 2, 25 a side view of the back of the same; Fig. 3, a muzzle end view; Fig. 4, a front side view with the front casing removed to show the construction; Fig. 5, a vertical sectional view on the line XX looking in the direction of the arrow, with some parts in front 30 of the section shown to indicate their relative position; Fig. 6, a detail perspective view of the trigger; Fig. 6a, a portion of the trigger; Fig. 7, a detail perspective view of 35 the hammer; Fig. 8, a similar view of the hammer pawl from the opposite side; Fig. 9, a side view of a cylinder modification, and Fig. 10, an end view of the same.

Referring to the drawing, the letters A 40 and B designate the front and back respectively of a stock, preferably round, flat, disk-like in shape and similar in outside appearance to an open-faced watch having a dial face and crystal C to carry out this 45 impression to a casual observer. The barrel D is short and has the appearance of being the stem to said watch, but extends a suitable distance inside the stock. The stock is recessed and divided as shown, or in any 50 other suitable manner, and is fastened together by screws E, or otherwise. The barrel is located somewhat out of the central plane of the stock, and nearer the front side, as shown in Figs. 1 and 3, so that the 55 axis of the barrel will line up with the re-

spective axis of each cartridge chamber of a revoluble cylinder F, similar in the main to that of a revolver, which is mounted on a pin G having a threaded end by which it is screwed into the wall H, Fig. 4, by the slot 60 at the outer end, or is otherwise secured. This preferred offset of the barrel brings the cylinder more nearly into the stock when a full cylinder is used as in Fig. 5; and the projection from the back side is yet further 65 reduced or avoided, by the modified cylinder or cartridge receptacle F' shown in Figs. 9 and 10, in which the sides I J retain three of the chambers, and may be reduced yet more. 70

With the full cylinder and seven chambers for .22 caliber as shown in Fig. 5, a cover K, preferably sliding in grooves in the back, fits snugly over the cylinder, and its forward end laps over a matching projecting end L from the back, and guards the palm of the hand from the explosion, when held by the operator as described in the patent above referred to. The cover is shown opened in Fig. 2, and closed in Fig. 80 1, and may be otherwise formed. The usual ratchet notches M on the rear end of the cylinder, corresponding to the number of chambers, are engaged successively by the cylinder ratchet pawl N, worked up and 85 down through a slot in the wall H by a hammer O to which it is pivoted on the screw pin P, by which means the chambers are successively alined with the barrel at the instant the hammer is released from the trigger as presently described. The said hammer is thick enough to give a good bearing 90 on the gudgeon Q, between the shoulder R and boss S that maintains its striking point T in the vertical plane through the axis of 95 the barrel and alined chamber with its cartridge. As shown, the hammer point is adapted for rim fire cartridges, but may be made lower for center fire. One of the screws E preferably passes through the center of the said gudgeon and screws into the boss S. A notch U in the hammer receives 100 one end of a strong spring V, the other end of which is fixed in the back, so as to return the hammer with sufficient force to explode 105 the cartridge.

A shoulder W, formed by a notch or otherwise, in the upper front side of the hammer and lateral to its striking point, constitutes a bearing for one end of a plate 110

pawl 2 that is pivotally mounted on the front side of a sliding plate trigger 3 by a slot and pin or other loose connection 4, so that both are movable back and forth parallel to the barrel and across the top of the hammer and cylinder, in a guiding recess 5. The head of the pawl 2 is formed in an arc 6 from the pivot 4 as a center, so as to drop in front of the shoulder W as shown in Figs. 4 and 5, with minimum amount of play, and to press straight to the pin 4 in starting the backward motion of the manner by pressure of the fore finger on the outer end 7 of the trigger. The head is also preferably thickened, and provided with a hook 8, or otherwise adapted to engage the trigger plate, so that the upward pressure of the shoulder W on the point of the pawl as the hammer is forced backward, will not lift the pawl and cause premature return of the hammer. The pawl and trigger slide backward as one piece and energize the hammer mechanism till the top of the shoulder W disengages from the head 6 as indicated in Fig. 4, when the hammer is returned against the cartridge by the tension of said spring V.

The trigger 3 is returned to its full outward position indicated by dotted line at 7' by a tension spring 9 secured to a pin 10 at the rear end, and to the forward end of the spring pocket 12. The trigger returning carries with it the pawl 2 till the point of the hook 8 strikes the back of the hammer, retards the pawl while the end of the trigger slips off the hook, and allows the slant side 13 to raise the head over the hammer and drop on the forward side of the shoulder W under the downward pressure of the spring 14. The pawl is beveled off toward the head on its upper side to allow this upward movement in the guiding recess, but its bottom edge is practically even with the bottom edge of the trigger and the guiding recess 5. The slot and pin connection previously referred to, allows sufficient play of the pawl to free the said hook as described. The striking pin and trigger are in different planes and do not interfere.

The sliding trigger has a pair of rear and front shoulders 15 and 16 respectively, formed by a notch 17 in its bottom edge, or otherwise, which are adapted at both ends of its stroke to check the cylinder in the successive alinement of the chambers with the barrel, by engaging suitable recesses in both rear and front ends of said cylinder.

Referring to Fig. 5, it will be seen that the bottom edge of the trigger lies in the path of the cylinder, and by making said notch of suitable length the rear shoulder 15 will engage recesses 18 when the trigger returns successively to its forward position. This engagement locks the cylinder till a backward movement of the trigger and hammer first frees the cylinder and then

causes the said ratchet pawl N to rotate it in the direction of the arrow to aline the next chamber, as indicated in Figs. 4 and 5. As the hammer nearly reaches its full rearward position, the front shoulder 16 of the trigger 76 enters the appropriately adjacent tapered notch 19 at the front end of the cylinder, and, at the instant of the hammer's disengagement, seats itself snugly in locking engagement. Since the trigger does not return till the hammer has discharged the cartridge, this last named locking engagement maintains the alinement of barrel and corresponding chamber during the resulting explosion therein. This taper fit of trigger 80 and recess by which accurate alinement of barrel and chambers is secured at the instant of firing, may be obtained by a taper on the recess as shown; or reversely by taper on the trigger shoulder 16', as in partial detail Fig. 6^a, or otherwise. 85

In use, the pistol is held in the palm of the hand with the fore finger above the stem barrel and on the trigger, while the other fingers and thumb embrace the edge. The initial pressure on the trigger takes up the play of the trigger pawl and brings the trigger to the position shown by full lines, Fig. 4, with the pawl hook engaging the end of the trigger and the head 6 bearing against 95 the hammer. Continued pressure alines a cartridge and snaps the hammer; relieving the pressure, sets the trigger for the next cartridge, thus making the pistol automatic and capable of firing all the cartridges in 100 the cylinder successively simply by repeated finger action on the one trigger.

As the usual place for carrying a watch is in the left vest pocket, this revolver is shown adapted for use in the left hand, so 105 that when pulled out with the right hand for instance by a chain attached to a link 20 at the front side of the stem-barrel, it will naturally seat itself in the palm of the left hand in operative position with the 110 forefinger on the trigger. If desired, however, this revolver can be made right handed and be carried in the right hand pocket, or elsewhere.

Having thus fully described my invention, 115 what I claim as new, and desire to secure by Letters Patent, is:

1. An improved revolver comprising a flat disk-like stock and short projecting barrel hidden therein on one side of a central 120 plane through the stock and adapted to lie in the palm of the hand, a chambered cartridge receptacle revolubly mounted in said stock on an axis parallel to said barrel but at the other side of the central plane of 125 said stock, means to revolve said cartridge receptacle to aline each chamber in succession with said barrel, and a trigger and hammer mechanism co-operating with said cartridge receptacle, 130

2. An improved revolver comprising a flat, disk-like stock, a short stem-like barrel and revolvable cylinder on parallel axes on opposite sides of the central plane of said stock, a sliding trigger located above said barrel and cylinder and adapted to engage the latter at both ends of its stroke, and a hammer mechanism coöperating with said cylinder and trigger for the purpose described. 25
- 10 3. A revolver comprising a stock, a barrel and its cylinder on parallel axes, a hammer mechanism coöperating with said cylinder, a sliding trigger, and a pawl having a slot and pin connection with said trigger, and 30 having a hook to engage said trigger while the hammer is engaged by said pawl, substantially as described.
- 15 4. A revolver comprising a stock, a barrel and its cylinder on parallel axes, a spring-controlled hammer having a shoulder, a plate trigger, and spring to return it, a 35 spring-controlled plate pawl having a loose connection with said trigger and provided with a thickened head and hook to engage
5. A revolver comprising a revolvable cylinder with suitable notches at each end, a sliding spring-controlled plate trigger having a notch forming shoulders adjacent to 30 the respective ends of said cylinder, and adapted to enter said recesses on the corresponding strokes of said trigger, substantially as and for the purpose described.
6. A revolver comprising a sliding trigger, a hammer mechanism and a spring-controlled pawl 2 having a hook 8, a head 6 with slant face 13, and loosely pivoted to 35 said trigger, thereby adapted to form an operative connection between said hammer mechanism and said trigger, substantially as and for the purpose described.

In testimony whereof I have affixed my signature in presence of two witnesses.

LEONARD WOODS.
